[57] CLAIM

The ornamental design for a hose retractor for gasoline pumps, as shown and described.

DESCRIPTION

FIG. 1 is a reduced perspective view of the hose retractor for gasoline pumps showing my new design;

FIG. 2 is a left side elevational view thereof;

FIG. 3 is a right side elevational view thereof;

FIG. 4 is a front elevational view thereof, the rear elevation being a mirror image thereof; and

FIG. 5 is a top plan view thereof.

The elevational views of the hose retractor in FIGS. 2-4 are shown broken away for ease of illustration.
